UNITED STATES PATENT OFFICE.

MICHAEL J. PURTLE, OF ERIE, PENNSYLVANIA.

CLAM-SHELL BUCKET.

No. 823,290.

Specification of Letters Patent.

Patented June 12, 1906.

Application filed February 26, 1906. Serial No. 303,114.

To all whom it may concern.

Be it known that I, MICHAEL J. PURTLE, a citizen of the United States, residing at Erie, in the county of Erie and State of Pennsylvania, have invented certain new and useful Improvements in Clam-Shell Buckets; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to clam-shell buckets, and has for its object the construction of a self loading and dumping bucket suitable for loading and unloading iron ore, sand, and other like materials.

20 The features of my invention are hereinafter set forth and explained and are illustrated in the accompanying drawings, in which—

Figure 1 is a side view in elevation of a clam-shell bucket embodying my invention.

25 Fig. 2 is an end view in elevation of the same.

In the drawings, A A indicate the two body portions of a clam-shell bucket, which are of usual and ordinary construction, hinged together at the upper portion of their adjacent 30 or open ends by the hinges a a, the pintle a' of which extends across the body of the bucket from one hinge to the other. In Fig. 2 this pintle a' is shown in dotted lines as passing through sleeves, as and for the purpose 35 hereinafter set forth. To the opposite or rear ends (see Fig. 1) of the body portions A A are pivoted upwardly-projecting links B B B B by means of pintles b' b', which extend entirely across the rear ends of the body portions A A and are shown in dotted lines in 40 Fig. 2 as passing through sleeves, as and for the purpose hereinafter set forth. The upper ends of these links B B and B B on each side of the bucket are preferably pivoted together upon the pintle b², which extends from 45 one side to the other through a sleeve C. If desired, however, the said links B may be pivoted to a yoke at their upper ends by separate pivots. The sleeve or yoke is also provided with an eye or loop c, by which the 50 bucket may be attached to a hoisting-cable D.

Mounted upon the pintles a and b in each of the body portions A A are levers E E E E, the shorter ends e of which extend over the 55 opposite body portion A. I preferably use four of these levers E—two over each body

portion A; but it is obvious that the bucket may be constructed with but two levers E—one over each body portion A—or with a greater number, as desired, or said levers E 60 may be mounted outside of the bucket upon the pintles a and b without departing from the spirit of my invention. To the upper or short ends e of the levers E, I pivot links F (a link F for each lever E) by means of pivots f. 65 The upper ends of the links F on each side of the bucket are inclined toward each other until they are in line, when a pintle G is passed through holes in their upper ends, thus pivoting all of said links F together upon 70 a common pivot.

In Fig. 2 the pintle G is shown in dotted lines as passing through short sleeves or thimbles between the upper ends of the links F. I also preferably mount upon the pintle 75 G a sheave H, around which operates a closing-cable I, which is shown in Fig. 1 attached to the yoke C at the upper ends of the links B. The sheave H may be dispensed with and the cable I secured permanently to the 80 pintle G or to the upper ends of the links F; but I prefer to use the sheave, as it produces a draft-line for the links F directly in line with the cable D.

In operation when the bucket is being lowered upon the material to be lifted the cable I is slackened, while the cable D is held taut, which permits the adjoining hinged ends of the body portions A A of the bucket to drop, the rear ends thereof being held up by the 90 cable D, and thereby the portions A A and the levers E and links F are lowered until the body portions A are opened to their greatest extent, when the two cables D and I are simultaneously slackened and the bucket 95 dropped upon the iron ore or sand to be lifted. After the bucket has thus been dropped in an open condition upon the material to be lifted the lifting strain is put upon the closing-cable I, which operates through the links 100 F and levers E to close the body portions A A upon each other, at the same time scraping up a large quantity of material. When the bucket has been closed by the cable I, the lifting strain is placed upon both of the cables D and I, and they operate jointly to lift the bucket, with its load of material, and transport it to the dumping-place, where the closing-cable I is slackened, which permits the body portions A A of the bucket to open 105 downward and dump the load of material.

Having thus fully described my invention,

so as to enable others skilled in the art to which it appertains to construct and operate the same, what I claim as new, and desire to secure by Letters Patent of the United States, is—

1. In a clam-shell bucket the combination of body portions hinged together at their inner or adjacent ends, upwardly-extending links pivoted to a yoke at their upper ends, pivoted to the rear or outer ends of said body portions, a hoisting-cable secured to the yoke at the upper ends of said links, levers secured to each body portion having shorter ends extending past the end of the opposite body portion, links pivoted to the short ends of said levers and means adapted to exert a lifting strain upon the upper ends of said links, substantially as and for the purpose set forth.
2. In a clam-shell bucket the combination of body portions hinged together at their inner or adjacent ends upon a pintle extending across the bucket from one hinge to the other, upwardly-extending links pivoted to a yoke at their upper ends, pivoted to the rear or outer ends of said body portions upon pintles which extend across said rear ends from side to side, a hoisting-cable secured to said yoke, levers mounted upon said pintles with the short ends thereof extending over the oppo-

site body portion, links pivoted to the short ends of said levers, a pintle passing through the upper ends of said links, and a closing-cable adapted to exert a lifting strain upon said pintle, substantially as and for the purpose set forth.

3. In a clam-shell bucket the combination of body portions pivoted together at their inner or adjacent ends, a pintle extending through the hinge on each side of the bucket, upwardly-extending links pivoted upon a yoke at their upper ends, pivoted to said body portions upon pintles extending across the rear ends of said body portions, a hoisting-cable secured to said yoke, levers mounted upon said pintles with their short ends extending over the opposite body portions, links pivoted to said levers, a pintle passing through the upper ends of said links, a sheave mounted upon said pintle, and a closing-cable operating around said sheave, substantially as and for the purpose set forth.

In testimony whereof I affix my signature in presence of two witnesses.

MICHAEL J. PURTLE.
